UNITED STATES PATENT OFFICE.

THOMAS P. BOLGER, OF GLOUCESTER, MASSACHUSETTS, ASSIGNOR TO SUCCESS MANUFACTURING COMPANY, OF GLOUCESTER, MASSACHUSETTS, A CORPORATION OF MASSACHUSETTS.

ASH-SIFTER.

971,018.

Specification of Letters Patent. Patented Sept. 27, 1910.

Application filed May 12, 1906. Serial No. 316,513.

To all whom it may concern:

Be it known that I, THOMAS P. BOLGER, a citizen of the United States, residing at Gloucester, in the county of Essex and State 5 of Massachusetts, have invented a new and useful Improvement in Ash-Sifters, of which the following is a specification.

This invention relates to ash sifters and more particularly to shaking sifters, the object being to provide an inclosed sifter so constructed that it can be readily placed over a barrel so that ashes can be sifted without any dust to amount to anything.

Another object of my invention is to provide the sifter with an inclined shaking sieve arranged under the bottom of the hopper and extending out under a removable top so that the ashes can be easily removed if they become clogged.

20 This invention consists of the novel features of construction, combination and arrangement of parts, hereinafter fully described and pointed out in the claim.

In the drawings forming a part of this 25 specification:—Figure 1 is a perspective view of my improved sifter attached to a barrel. Fig. 2 is a perspective view of the sifter attached to a barrel showing a bucket attached. Fig. 3 is a longitudinal sectional 30 view of the sifter. Fig. 4 is a section taken on lines 4—4 of Fig. 3. Fig. 5 is an inverted plan view of the sifter.

Referring to the drawings A indicates a metal cap adapted to fit snugly over the ordinary barrel having a square opening in the top over which the square opening of the casing B, is adapted to be secured which is provided with an inclined end B', having a hopper C, extending upwardly therefrom, provided with a hinged top C'. The side B², of the casing tapers downwardly from the hopper having outwardly flanged upper edges B³, over which the guide-edges D, of the top D, are adapted to fit. The top D, is 40 provided with a flanged end D², adapted to engage the flanged upper edges of the end B⁴, of the casing, which has a spout E, connected thereto, and to the bottom of the bottom of the casing. A hook F, is secured on 45 the outside of the end adapted to support the bucket under the spout. An opening D³, is formed in the top D, adjacent its upper end in which the bowed portion G', of a

spring G, secured to the hopper, is adapted to fit and securely lock the upwardly projecting flange D⁴, against the outer face of the hopper, when the top is pushed upwardly by the handle D⁵. Brackets H, are secured on the inside of the side of the casing on which the side bars of the sieve I, are adapted to 55 slide. The upper end of the sieve being provided with a handle J which extends out through an opening C², in the hopper under the inclined bottom plate C³, by means of which the sieve is worked back and forth so 60 to cause the ashes to drop through the sieve into the barrel and the coal and cinders to slide downwardly over the sieve out the spout into the bucket. The plate C³, forms a guide or chute which directs the ashes fed 65 through the hopper, into the sieve, and prevents the ashes from passing into the barrel or other receptacle before being sifted, when the sieve is slid forward during the shaking operation. The top A, being provided with 70 an inclined plate A', formed by turning up a part of the top at one end of the opening so that the ashes at the lower end of the sieve will drop into the plate and slide into 75 the barrel.

80 From the foregoing description it will be readily seen that I have provided a very novel sifter which is very simple and cheap in construction and one which is very effective in use.

Having thus fully described my invention, what I claim as new and desire to secure by Letters Patent:—

An ash sifter comprising a cap, a casing carried by the cap, a hopper supported by 90 the casing and having a side opening, the said casing extending beyond the cap, a spout carried by the casing, an inclined, slidably mounted sieve arranged within the casing and extending under the hopper, a 95 handle connected to the upper end of the sieve and working through the opening in the hopper, an inclined plate arranged above the upper end of the sieve, and an inclined plate arranged below the lower end of the 100 sieve, said plates respectively directing ashes upon the sieve and through the cap.

THOMAS P. BOLGER.
